J. G. MACKINTOSH'S

DESIGN FOR A TRADE MARK

PATENTED
SEP 24 1867

Fig. 1

United States Patent Office.

J. G. MACKINTOSH, OF NEW YORK, N. Y.

Design No. 2,786, dated September 24, 1867.

DESIGN FOR A TRADE-MARK.

The Schedule referred to in these Letters Patent and making part of the same.

TO ALL WHOM IT MAY CONCERN:

Be it known that I, JOHN G. MACKINTOSH, of the city, county, and State of New York, have originated and produced a new Design for a Trade-Mark, of which the following is a full, clear, and exact description, reference being had to the accompanying drawing or engraving, making a part of this specification.

The essential features of said design are the words "Scotia Mills," printed in Roman letters, as shown and a shield-shaped device bearing upon its face the letters "J. G. M." in script. The words "Scotia Mills" are arranged upon the arc of a circle, and bordered above with curved lines extending in a direction nearly parallel to the arc in which the words "Scotia Mills" are arranged. The shield-shaped device is placed immediately beneath the said words, and has eight sides, all slightly curved. The edges of this device are slightly bevelled, and the shield is shown in relief. The letters "J. G. M.," in script, are placed in a right line across the face of this shield, at a point about midway of its length. This shield is bordered by ornamental scroll work, the same being shown as springing from the edges of the shield. The said design may be made in bronze or gilt, as shown, or in any color desired.

The use and application of said design is as a "cloth-ticket," so called, being intended to be attached to pieces of woven cloth of a certain quality or manufacture. The two bordering lines of said "cloth-ticket," being parallel for the greater portion of their length, I do not regard as an essential part of the design, nor do I desire to be confined to the use of the two external border lines shown; but the words "Scotia Mills," printed in Roman letters, and arranged upon or in the arc of a circle, the centre of which is below said letters, used in combination with the shield-shaped device placed beneath said words, as described, and bearing on its face the letters J. G. M., in script; the whole, together with the said bordering devices above the said words and around said shield, being formed and arranged substantially as described, I consider to be and to constitute a new design for a trade-mark.

What I therefore claim as my invention, and desire to secure by Letters Patent, is—

The design for a trade-mark, substantially as herein set forth and shown.

J. G. MACKINTOSH.
